UNITED STATES PATENT OFFICE.

GEORGE S. EMERICK, OF PHILADELPHIA, PENNSYLVANIA.

PEBBLE-MILL.

No. 820,559.

Specification of Letters Patent.

Patented May 15, 1906.

Application filed June 26, 1905. Serial No. 266,971.

To all whom it may concern:

Be it known that I, GEORGE S. EMERICK, a citizen of the United States, residing at No. 125 Osborne street, Wissahickon, Philadelphia, in the county of Philadelphia and State of Pennsylvania, have invented certain new and useful Improvements in Pebble-Mills, of which the following is a specification.

My invention relates to the class of mills for reducing, comminuting, or grinding, known as "ball," "tube," or "pebble" mills, wherein the substance to be reduced is fed into a rotating cylinder containing pebbles and subjected to the grinding action of the pebbles, caused by the rotation of the mill.

My improvement in this class of mills consists in a novel form of head located at the inlet or feed end of said mill, whereby an ample and rapid feed of material into the body of the mill may be secured, while at the same time the egress of the pebbles into the feed-trunnion and feed-worm is effectually prevented. This result I accomplish by the means shown and described in the accompanying drawing, in which the figure is a view in vertical section of a ball or pebble mill furnished with my improved head.

In the figure, A is the drum or cylindrical body of the mill, adapted to be rotated horizontally either by means of the guides or rails B upon the circumference of said drum A in conjunction with the wheels C, actuated by any suitable mechanism or by means of its trunnions D and D' in the well-known manner.

The admission of the material to be comminuted or ground is effected by means of the pipe or worm-casing E and the worm F, actuated by its pulley G. The material carried by said worm is discharged through the opening H in the end of the worm-casing into the cone-shaped interior of the feed-trunnion D. From the feed-trunnion D the material passes into the body A of the mill through the head I, I', I'', and I'''. The construction of this head is as follows: The part I is a disk. The parts I', I'', and I''' are rings disposed parallel to said disk and to each other, the whole being bolted or otherwise appropri-

ately secured to the inlet end of the drum A, as shown in the drawing. It is to be observed that the ring-like form of the parts I', I'', and I''' admits of a feed of material through four annular spaces or openings—viz., between the end wall of the drum A and the part I''', between I''' and I', between I'' and I'', and between I''' and I.

The disk and rings making up the head, as shown and described, should be so spaced as to exclude the passage between them of the pebbles employed in reduction, for the level of the load-line *x x* being above that of the inlet or feed-trunnion and feed-worm such an escape of the pebbles would result in a complete clogging of the inlet-trunnion, with, in all probability, a breakage of the feed-worm. It is thus apparent that by the form and arrangement of parts in my improved head I am enabled to effectually prevent the escape of pebbles into the inlet-trunnion while at the same time furnishing a means for the rapid feed of material into the mill, the rate of feed being of course proportionate to the number of auxiliary rings used in making up the head.

The exit of the reduced material is effected through the openings K in the disk L, and likewise through the annular space formed between the circumference of said disk and the end wall of the drum A. Thence it passes out by way of the outlet-trunnion D'.

What I claim as my invention, and desire to secure by Letters Patent, is—

The combination in a ball-mill of a feed mechanism therefor, consisting of a non-perforated plate or disk and a ring-shaped plate or disk spaced between the said non-perforated plate and the feed end of the mill-cylinder, said non-perforated plate and ring-shaped plate being parallel each to each substantially as described.

In testimony whereof I affix my signature in presence of two witnesses.

GEORGE S. EMERICK.
